Specification for Design.

Patented Aug. 10, 1915.

Application filed June 11, 1915. Serial No. 33,597. Term of patent 7 years.

To all whom it may concern:

Be it known that I, EGBERT B. SHEPARD, a citizen of the United States, residing at Providence, in the county of Providence and State of Rhode Island, have invented a certain new, original, and ornamental Design for a Precious or Semiprecious or Synthetic Stone or an Imitation Thereof, of which the following is a specification.

In the accompanying drawings which

form a part of this specification, Figures 1, 2, 3 and 4 are a top plan view, end elevation, side elevation, and bottom plan view, respectively of a cut stone embodying my design.

I claim:—

The ornamental design for a precious, or semiprecious, or synthetic stone or an imitation thereof, as shown.

EGBERT B. SHEPARD.
